UNITED STATES PATENT OFFICE.

WALTER E. LE ROY, OF CINCINNATI, OHIO, ASSIGNOR TO UNION SPECIAL MACHINE COMPANY, OF CHICAGO, ILLINOIS, A CORPORATION OF ILLINOIS.

ONE-PIECE SHIRT-PLAIT FOLDER.

Application filed February 24, 1925. Serial No. 11,188.

The invention relates to new and useful improvements in shirt plait folders, and more particularly to a folder which is so formed that the plait itself may be made from one piece of material, and wherein the parts of the folder may be separated for the insertion of the material.

An object of the invention is to provide a folder of the above type with a treadle controlled mechanism for separating the parts of the folder to permit the insertion of the material.

Another object of the invention is to provide a machine of the above type with means for locking the sections of the folder in their separated position while the material is being placed over and into the folder, or when threading the needles.

In the drawings which show by way of illustration one embodiment of the invention—

Figure 1 is a front view of the machine embodying the improvements;

Fig. 2 is an end view of a portion of the machine;

Fig. 3 is a view partly in section and partly in plan of a machine equipped with the improved folder;

Fig. 4 is a sectional view on the line 4—4 of Fig. 3;

Fig. 5 is a perspective view through a portion of a garment having the plait formed thereon by the improved folder;

Fig. 6 is a view partly in plan and partly in section of the article formed on the folder;

Fig. 7 is an enlarged front view of the latch mechanism, and

Fig. 8 is a view of the same from the end of the machine.

The invention includes broadly a folder for producing a one-piece shirt front, commonly known in the trade as a "Manhattan shirt front". This shirt front includes a folding of the edge of the garment underneath along a line parallel with the center of the front, and also the forming of a fold in the material, and the tucking of the folder part underneath the plait so as to form the other side thereof. This, in effect, forms the plait with the sides thereof turned underneath, but the plait is formed from one piece of material. The plait so formed may be provided with a facing strip on the in or under side thereof. The folder is made in sections which are movable laterally relative to each other in order to

make the fold in the body of the material and thus form one side of the center plait. These sections of the folder are so mounted that they may be moved relative to each other to aid in the insertion of the material, and the movable section is preferably controlled by a treadle; so that the operator by stepping on the treadle, may separate the sections, and then after placing the material on and in the folder, release this movable section, so as to enable the infolding of the material for the center plait.

The machine to which the invention is applied may be of any desired construction, but should preferably be of a two-needle type forming two spaced parallel lines of stitching.

In the drawings, the machine is shown as consisting of a bed plate 1 carrying the overhanging arm 2 in which a needle bar 3 reciprocates, which needle bar carries two needles, 4 and 5. A suitable complementary stitch forming mechanism cooperates with these needles so as to form two independent lines of stitching. The cloth plate is indicated at 6. The material is held on the cloth plate by a presser foot 7 of the usual construction. The presser foot is provided with two needle openings 8 and 9 adapted to receive the needles 4 and 5, respectively. The needles are shown as arranged in a line diagonal to the line of feed, so that independent threaded loopers may be arranged below the cloth plate for cooperating with these needles. The center plait folder comprises two sections 10 and 11. The section 10 includes an edge turning member 12, which turns one edge of the material from which the center plait is formed about the hollow core 13 through which the reinforcing strip is led.

This edge turning member is rigidly mounted on the base member 14. Said base member 14 is secured to the cloth plate 6 by means of screws 15, 15. The base member 14 also carries a shelving or rest plate 16 which is provided with an opening 17, 17 through which the screws 15 may be reached for turning the same into the cloth plate. The material to be folded to form the center plait rests on and moves along this shelving or rest plate 16, and its free edge extends across the core 13 and is turned by the edge turning member 12 underneath said core. In Figures 5 and 6 of the drawings, the article produced on the folder is shown in detail. Said article con-

sists of a body fabric 18 and the edge 19 thereof is turned underneath at 20 by this edge turning member 12. The opposite side 21 of the center plait is formed by making a fold 5 in the body fabric about the other edge of the hollow core 13. This is accomplished by an edge turning member 22 which is a part of the member 11 referred to above. This member 11 is carried by an arm 23 and is secured 10 thereto by means of an angle bracket 24 attached to the arm by screws 25, 25. The arm 23 is pivoted at 26 to a bracket 27 carried by the head of the machine (see Figures 1 and 2). The arm can swing on this pivot, and 15 when it is swung to the right, it will carry the member 11 to the position indicated in dotted lines in Fig. 4. This, of course, will expose the right-hand side of the center core 13, and allow the fabric to be laid along the shelf 16, 20 over the core, and the free edge of the fabric turned by the turning member 12, underneath the left-hand edge of this hollow core. When the member 11 is returned to the position 25 shown in full lines in Fig. 4, the edge portion 28 of the member 11 will make a bend or fold in the material as indicated at 29 in Fig. 5 of the drawings. The upper portion of the turning member 22 extends over the core 13 and will hold the top portion of the 30 plait flat and smooth and prevent the edge 28 from pulling unnecessary cloth from the body fabric. This folding of the material by this edge 28 of the member 11 brings the right-hand edge of the center plait a sufficient 35 distance underneath the center core, so that as the formed center plait passes off this center core, it will be secured in a folded position by the stitches *s* which are formed by the right-hand needle 5. There is also a line 40 of stitches *s'* formed by the left-hand needle 4, which passes down through the folded under edge portion on the left of the center plait and secures these parts together.

A reinforcing or interlining strip 30 is preferably led through this center core 13, and this reinforcing or interlining strip extends from one folded edge of the center plait to the other edge thereof, and the lines of stitching *s*, *s'* will pass through the strip. This reinforces 45 and gives shape to the center plait.

A facing strip 31 may be led through the guiding member 32. This guiding member is secured to a bracket 33, which in turn is secured to the cloth plate 6 by suitable screws 55 34, 34. This guide 32 is provided with means for turning over the edges of the facing strip as indicated in Fig. 5, and these overturned edges and the facing strip are so positioned relative to the center plait that the stitches *s* and *s'* will pass through the facing strip and 60 secure all the parts together. Other means may be provided for finishing the under face of the center plait, if desired, but I prefer to use a facing strip therefor. The facing strip is led 65 into the guide 32 from the right-hand as

viewed in Figures 1 and 3, and by a guiding member 36 which carries the same inwardly until it is in a line with the center plait folder, at which point, the strip is turned at right angles and led into the guide 32. The reinforcing or interlining strip is led into the core 13 from the left as viewed in Figures 1 and 3 by a guiding member 35. This center core 13 is mounted on the bracket members 37, 37 which in turn are mounted on the under side 70 of the shelving 16 carried by the bracket member 14. The upper wall of the center core 13 extends some distance in front of the center plait folder proper, and is mounted on these brackets 37, 37. The under wall of the core 75 13 is formed as a part of the guide 35. The reinforcing or interlining strip for reinforcing the center plait passes along this guide 35, and when it reaches the line of feed of the machine, it is turned at right angles and passes 80 through the core which leads the strip within the formed center plait. The member 36 is provided with guiding loops 38, 38 for guiding the strip along its under face. Likewise, the member 35 is provided with similar 85 guiding loops 39, 39 for guiding the facing strip along the under face of this member.

As noted above, the member 11 is carried by the swinging arm 23 which is pivoted at 26 to a bracket carried by the head of the machine. A link 40 is pivoted at 41 to this arm 23 and at its other end is pivoted at 42 to a lever 43. This lever is fulcrumed at 44 on a pivot screw which is attached to the bed plate 1 of the machine. The lever intermediate 95 its ends is attached to a coiled spring 45 which is anchored at 46 to the bed plate of the machine. This spring normally turns the lever 43 to the left, and this moves the arm 23 and the parts carried thereby to their lowermost 100 position, or operating position in the folder. After the fabric has been laid upon the shelf, and across the core 13 and the edge turned underneath at the left by the edge turning member 12, then the arm 23 is released so that 105 the spring may move the arm to the full line position in Fig. 4, and as it moves to this position, the part 28 will make a fold in the fabric and carry this fold in part, underneath the right-hand side of the core, and thus it is that 110 the fabric is folded about the core 13 and the center plait formed.

Mounted on the lever 43 is an arm 47 which is rigidly secured to said lever 43. A link 48 is connected at its upper end to this arm 47 115 and at its lower end to a treadle or knee press lever, so that the operator can readily move the lever 43 to swing the arm 23 and thus move the section 11 of the center plait folder to the dotted line position in Fig. 4. When the 120 lever is swung to the position shown in full lines in the drawings, the lever comes in contact with the adjustable stop 49. Said lever extends beneath a bridging piece 50 and contacts with the adjustable stop 49. When the 125 130

link 48 is pulled down, said link will swing the lever 43 until the end 51 of said lever strikes the adjustable screw 52 which limits any further movement of the lever 43. In order to secure this lever with the parts in the dotted line position as shown in Fig. 4, a latch 53 has been provided. Said latch is pivoted at 54 to the bed plate 1 of the machine, and may be swung over the outer end of the projection 10 51 on the lever 43 and lock these parts in this inoperative or negative position.

In Figs. 7 and 8 of the drawings, I have shown a portion of this mechanism where it is apparent that the latch engages the end 15 51 of the lever 43 in such a way as to lock the parts. The latch may be readily released by the operator when it is desired that the part 11 shall swing to the full line position and form the right-hand side of the center 20 plait.

From the above construction it will be apparent that I have provided a center plait folder made in sections which may be readily separated for the insertion of the material, 25 and which may be locked in said separated position until the material has been placed in and on the folder, after which the movable section may be released and automatically returned to proper position for completing the 30 formation of the center plait.

It will be obvious that changes may be made in the details of construction of the center plait folder and the arrangement of parts, the essential feature consisting in the forming 35 of this center plait folder in sections, whereby said sections may be readily separated to permit the insertion of the material, and wherein said separation may be brought about by devices under the control 40 of the operator, which may be actuated without interfering with the operator guiding the material into and through the folder.

In order to flatten the reinforcing or interlining strip and thereby cause the proper 45 shaping of the plait, the outer portion of the guiding core 13 is extended and has its side edges thereof tapered outwardly as indicated at 55, in Fig. 3 of the drawing. This end is also slightly turned downwardly 50 as shown in Fig. 2. As the strip runs underneath this end portion, it will be flattened, and as the end portion is also located within the plait which is passing out from the folder, it will assist not only in the flattening of 55 the reinforcing or interlining strip, but in the proper straightening of the formed plait for the stitching thereof.

Having thus described the invention, what I claim as new and desire to secure by Letters-Patent, is—

1. A center plait folder for sewing machines comprising a hollow core for guiding a flat reinforcing strip, a main section spaced from said hollow core and extending about 65 one edge thereof so as to direct and infold

one edge portion of a center plait about one edge of said reinforcing strip, means for supporting said main section in fixed position, a section movable laterally relative to said stationary main section and extending about the opposite edge of said hollow core for guiding and infolding the other edge of a center plait about the opposite edge of the reinforcing strip, and manually controlled devices for shifting said movable section away from 70 said fixed section and core to aid in the placing of the material for forming the center plait.

2. A center plait folder for sewing machines comprising a hollow core for guiding a flat reinforcing strip, a main section spaced 80 from said hollow core and extending about one edge thereof so as to direct and infold one edge portion of a center plait about one edge of said reinforcing strip, a movable section extending about the opposite edge of said hollow core for guiding and infolding the other edge of a center plait about the opposite edge of the reinforcing strip, and manually controlled devices for shifting said 85 movable section to aid in the placing of the material for forming the center plait, said manually controlled devices including a spring for normally pressing said movable section into position for guiding and infolding the strip forming the plait.

3. A center plait folder for sewing machines comprising a center member around which a strip may be folded for forming the plait, a main folding section fixed relative to said center member at one side thereof and extending about the edge of said center member and over one side portion thereof for guiding and infolding one edge portion of the strip forming the center plait, 100 and a movable folder section spaced from and extending over and underneath the other edge portion of said center member for infolding the other edge of the strip forming the center plait.

4. A center plait folder for sewing machines comprising a center member around which a strip may be folded for forming the plait, a main folding section fixed relative to said center member at one side thereof and extending about the edge of said center member and over one side portion thereof for guiding and infolding one edge portion of the strip forming the center plait, and a movable folder section spaced from and extending 105 over and underneath the other edge portion of said center member for infolding the other edge of the strip forming the center plait, said center member being hollow whereby a reinforcing strip may be placed within said 110 center plait.

5. A center plait folder for sewing machines comprising a center member around which a strip may be folded for forming the plait, a main folding section fixed relative to 130

said center member at one side thereof and extending about the edge of said center member and over one side portion thereof for guiding and infolding one edge portion of the strip forming the center plait, a movable folder section spaced from and extending over and underneath the other edge portion of said center member for infolding the other edge of the strip forming the center plait, and 10 manually controlled means for shifting the movable folder section to aid in the placing of the strip in the folder.

6. A sewing machine including stitching mechanism having spaced needles for forming independent lines of stitching, a center plait folder comprising a hollow core for directing the reinforcing strip to said needles, means supported in fixed position for folding one edge of the fabric underneath said core 15 for forming one side of the center plait, a section movable laterally relative to said core for folding the fabric around said core at the other side of said folder for forming the other side of said center plait, said folded portions of the fabric being presented to the needles so that the needles pass through the 20 25

respective sides of the plait and the reinforcing strip enclosed within the plait.

7. A sewing machine including stitching mechanism having spaced needles for forming independent lines of stitching, a center plait folder comprising a hollow core for directing the reinforcing strip to said needles, means supported in fixed position for folding one edge of the fabric underneath said core 30 for forming one side of the center plait, a section movable laterally relative to said core for folding the fabric around said core at the other side of said folder for forming the other side of said center plait, said folded portions 35 of the fabric being presented to the needles so that the needles pass through the respective sides of the plait and the reinforcing strip enclosed within the plait, the upper wall of said hollow core being extended and having 40 its side edges tapered outwardly to flatten the reinforcing strip and straighten the formed center plait prior to the passing of the same to the stitching mechanism. 45

In testimony whereof, I affix my signature.

WALTER E. LE ROY.
